(57) **CLAIM**

The ornamental design for a western blot processor, as shown and described.

DESCRIPTION

FIG. 1 shows a front left perspective view of the western blot processor;

FIG. 2 shows a front right perspective view of the western blot processor;

FIG. 3 shows a left side perspective view of the western blot processor;

FIG. 4 shows a right side perspective view of the western blot processor;

FIG. 5 shows a right side view of the western blot processor; and,

FIG. 6 shows a front elevation view of the western blot processor.

The broken lines in the drawing views are included for the purpose of illustrating a portion of the western blot processor that forms no part of the claimed design.
